DUPLICATING APPARATUS

Alfred Marchev, La Grange, Ill., assignor to
Ditto, Incorporated, Chicago, Ill., a corpora-
tion of West Virginia

Application March 29, 1937, Serial No. 133,577

7 Claims. (Cl. 101—132)

The invention relates to duplicating apparatus and is particularly adapted to be embodied in duplicating machines of the type wherein copy sheets are moistened and are applied to a master sheet upon which the data to be copied has been written or typewritten in reverse.

A particular object of the invention is to provide a duplicating machine of the character described having improved means for assisting the operator to secure the master sheet in the machine and to replace it with another.

One form of the invention is embodied in a duplicating machine of the kind described comprising a duplicating drum to which the master sheets may be secured detachably, a platen roller for pressing copy sheets against the master sheets, means for moistening the copy sheets as they are advanced to the duplicating drum, means for releasably clamping one edge of the master sheet to the drum, a table or guide upon which the master sheet is placed when it is to be clamped to the drum, and a manually operable lever for opening the clamping means and for aligning the drum with the table or guide from which the master sheet is to be advanced to the clamping means.

Other objects and advantages will become apparent as the following detailed description progresses, reference being had to the accompanying drawings wherein—

Fig. 1 is a side elevation, partly broken away, of a duplicating machine which embodies the invention;

Fig. 2 is a fragmentary plan elevation of the improved machine;

Fig. 3 is a fragmentary section taken on line 3—3 of Fig. 2;

Fig. 4 is a section taken on the same line as Fig. 3, but showing certain parts in changed positions;

Fig. 5 is a fragmentary section taken on line 5—5 of Fig. 3; and

Fig. 6 is a fragmentary section taken on line 6—6 of Fig. 2.

Referring to the drawings wherein a preferred embodiment of the invention is illustrated, the reference character 10 designates generally the frame of the machine, in which frame is rotatably journaled a duplicating drum which is designated generally by the reference character 11. Cooperating with the duplicating drum 11 is a platen roller 12 to which copy sheets are fed by combined moistening and feeding rolls 13 and 14, the roll 13 being supplied with solvent from a reservoir 15 which is connected by a conduit

(not shown) to a tank 18 mounted in the frame 10. The tank 18 holds a supply of solvent and this solvent is pumped from the tank 18 to the reservoir 15. The pumping means do not form part of this invention and need not be described.

Projecting forwardly from the frame 10 is a table 20 upon which a stack of copy sheets may be placed and advanced, manually, one by one to the combined feeding and moistening rolls 13 and 14. As the copy sheets are advanced between the rolls 13 and 14, the roll 13 applies a film of solvent to the upper surface of each copy sheet. The solvent is one which will dissolve data written or typewritten upon a master sheet in reverse. A master sheet may be made by placing it against the carbon surface of a carbon sheet and typewriting or writing upon the front side of the master sheet so that the data will appear in reverse on the back of the sheet. The master sheet is then secured to the drum 11 in such manner that the writing or typewriting in reverse is on the outer side as the master sheet is trained around the drum. When the copy sheets are advanced by the rolls 13 and 14, they pass between the duplicating drum 11 and the platen roller 12 and are pressed against the master sheet on the drum to obtain a copy thereof. A relatively large number of copies of the master sheet may be obtained in this manner.

The means for rotating the drum 11 preferably comprises a handle 22 fixed to a pin 23 rotatably journaled in the frame 10. Constrained to rotate with the pin 23 is a pinion 24 which meshes with a gear 25a with which the drum 11 is constrained to rotate. The construction is preferably such that two revolutions of the handle 22 causes the drum 11 to make one revolution. During this revolution one copy sheet is applied to the master sheet and discharged onto a copy sheet table 24 detachably secured to the frame 10.

The means for securing a master sheet to the drum 11 preferably comprises a clamping bar 25' mounted in a relatively wide and shallow slot 26 extending longitudinally of the drum 11 and across its entire cylindrical surface. A plurality of springs 27 disposed in bores 28 formed in the bar 25' yieldingly urge the bar 25' toward a shoulder 30 at one end of the slot 26. It will be readily understood that the forward edge of a master sheet 31 may be inserted between the bar 25' and the shoulder 30 so that the bar 25' will clamp it against the shoulder as shown in Fig. 6. A plurality of springs 33 extending between the drum 11 and the bar 25' hold the bar in place in

the slot 26 but permit the bar to move edgewise to clamp the forward edges of the master sheets. Pins 34 project from the bar 25' into the drum 11 which is hollow. Engageable with the pins 34 are disks 35 fixed to a shaft 36 which is journaled in the drum 11 and may be rotated by a pin 37 projecting from a collar 38 fixed to one end of the shaft 36. Each of the disks 35 has a flattened surface 39 in its periphery and when the flattened surfaces 39 are opposed to the pins 34 as illustrated in dotted lines in Fig. 4, the bar 25' is free to clamp the forward edge of a master sheet to the shoulder 30. However, when the shaft 36 is displaced angularly into the position wherein it is shown in Fig. 6 so that the flattened surfaces 39 are not opposed to the pins 34, the peripheries of the disks 35 acting against the pins 34 hold the bar 25' in a retracted position against the action of the springs 27.

20 A table 40 is provided upon which table a master sheet may be placed when its forward edge is to be clamped to the drum 11. Obviously, the shoulder 30 or rather, the slot formed between the shoulder 30 and the adjacent edge of the bar 25' must be aligned with the table 40 if the master sheet resting thereon is to be advanced into the slot. Means is provided for bringing the drum and holding it in a position wherein the slot between the shoulder 30 and the bar 25' will be aligned with the table 40. This means preferably comprises a hand lever 42 pivoted upon a pin 43a mounted in the frame 10. A lug 43' is struck or stamped from the lever 42 and projects inwardly toward the drum 11. A second lug 44 is spot welded or otherwise secured to the lever 42 and also projects inwardly toward the drum 11. Projecting from one end of the drum 11 is a pin 45 adapted to engage the lug 43' when the lever 42 is swung into the position wherein it is shown in full lines in Fig. 3. When the pin abuts the lug 43' as illustrated in Fig. 3, the slot between the shoulder 30 and the bar 25' is aligned with the master sheet table 40. The lug 44 is longer than the lug 43' and is adapted to engage the pin 37 when the lever 42 is in the position wherein it is shown in full lines in Fig. 3. It will be readily understood that if the lever 42 is swung into the position wherein it is shown in full lines in Fig. 3 and the drum 11 is being rotated in a counter-clockwise direction (Fig. 3), the pin 37 will strike the lug 44 and continued rotation of the drum 11 will cause the lug 44 to displace the pin 37 and the shaft 36 angularly until the disks 35 are brought from the position wherein they are shown in dotted lines in Fig. 4 to the position wherein they are shown in dotted lines in Fig. 3 so that the bar 25' will be retracted from the shoulder 30. The pin 45 is located upon the drum 11 so that when the disks 35 assume the positions wherein they are illustrated in Figs. 3 and 6, the pin 45 will be in engagement with the lug 43' and the operator cannot continue to rotate the drum 11 in a counter-clockwise direction (Fig. 3). However, the operator may keep urging the pin 45 against the lug 43' to hold the drum 11 stationary while an old master sheet is being removed therefrom and a new one is inserted.

Any suitable means may be provided for driving the rollers 13 and 14. In this instance, the drum 11 has a gear 50 constrained to rotate with it and the gear 50 meshes with an idler pinion 51. The pinion 51 meshes with a pinion 52 with which the roller 13 is constrained to rotate. The roller 14 is driven by frictional engagement with the roller 13.

The operation of the above described apparatus is substantially as follows: If it is assumed that a master sheet is on the drum 11 and the desired number of copies have been made of it, it will be readily understood that the lever 42 may be 5 swung from the position wherein it is shown in full lines in Fig. 4 to the position wherein it is shown in full lines in Fig. 3 so that when the operator continues to rotate the drum 11, it will come to rest in the position wherein it is shown 10 in Fig. 3 so that the slot between the shoulder 30 and the bar 25' will be aligned with the table 40. The bar 25' will be in its retracted position. The operator may then remove the old master sheet and place a new master sheet 31 on the table 40 15 and then employ the table as a guide to advance the master sheet until its forward edge is disposed between the shoulder 30 and the clamping bar 25'. The operator may then retract the lever 42 into the position wherein it is shown in full 20 lines in Fig. 4 and also angularly displace the pin 37 to bring the flattened surfaces 39 into opposed relation with the pins 34 so that the springs 27 will cause the clamping bar 25' to clamp the forward edge of the master sheet against the 25 shoulder 30. Then when the operator continues to rotate the drum 11 in a counter-clockwise direction (Figs. 3 and 4), the master sheet is trained around the drum 11. The operator may then advance copy sheets to the combined feed- 30 and moistening rollers 13 and 14 as described above and copies may be made of the data on the master sheet.

It will be noted that the lever 42 rides in a slot 55 formed in a sheet metal housing 56 which 35 forms part of the frame 10. The slot 55 limits angular displacement of the lever 42 in both directions.

While I have shown and described certain embodiments of my invention, it is to be understood 40 that it is capable of many modifications. Changes, therefore, in the construction and arrangement may be made without departing from the spirit and scope of the invention as disclosed in the appended claims, in which it is my intention to 45 claim all novelty inherent in my invention as broadly as permissible, in view of the prior art.

I claim:

1. In a duplicating machine of the kind described, a rotatable drum, means for securing a 50 master sheet to said drum, means for pressing copy sheets against the master sheet on said drum, means for guiding a master sheet to said securing means, and means for aligning said securing means with said guide means, said aligning means 55 comprising a pivoted lever, means on said lever for engaging and opening said securing means to receive one edge of a master sheet, and means on said lever for engaging said drum and preventing rotation thereof in the direction it is 60 normally rotated whereby said securing means remain in alignment with said guide means.

2. In a duplicating machine of the kind described, a frame, a rotatable drum mounted in said frame, means for securing a master sheet 65 to said drum, means for pressing copy sheets against the master sheet on said drum, means for guiding a master sheet to said securing means and means for aligning said securing means with said guiding means, said aligning means comprising a member movably mounted on said frame, means on said member for engaging and opening said clamping means, and means on said member for engaging said drum and preventing rotation thereof in the direction it is normally 70 75 75

rotated whereby said securing means is held in alignment with said guide means.

3. In a duplicating machine of the kind described, a frame, a rotatable drum mounted in said frame, means for securing a master sheet to said drum, means for pressing copy sheets against the master sheet on said drum, means mounted on said frame to remain stationary in a functionally operative position for guiding a master sheet to said securing means, and means for aligning said securing means with said guide means, said aligning means comprising a lever pivoted on said frame, means on said lever for engaging said drum while it is being rotated in the normal direction and stopping it with the securing means in alignment with the guide means, and means on said lever for engaging and opening said clamping means during the final movement of said drum into the position wherein its securing means are aligned with said guide means.

4. In a duplicating machine of the kind described, a frame, a rotatable drum mounted in said frame, means for securing a master sheet to said drum, means for pressing copy sheets against the master sheet on said drum, means for guiding a master sheet to said securing means, and means for aligning said securing means with said guide means, said aligning means comprising a lever pivoted on said frame, a pin projecting from said drum, a lug on said lever engageable with said pin to stop said drum against movement in the normal direction and with its securing means in alignment with said guide means, and a second lug projecting from said lever for engaging and opening said securing means during the final movement of the drum into the position wherein its securing means are aligned with said guide means.

5. In a duplicating machine of the kind described, a frame, a rotatable drum mounted in said frame, means for clamping a master sheet to said drum, a shaft rotatably mounted in said drum, a pin projecting from said shaft, means controlled by said shaft for releasing said clamping means, yielding means for actuating said clamping means to clamp a master sheet to said drum, a table for holding a master sheet, and means for aligning said clamping means with

said table, said aligning means comprising a lever pivoted on said frame, a second pin projecting from said drum, a lug projecting from said lever and engageable with said second pin to hold said drum against rotation in the normal direction and in a position wherein its clamping means are aligned with said table, and a second lug on said lever for engaging and opening said securing means as said drum moves into the position wherein the securing means are aligned with said table.

6. In a duplicating machine of the kind described, a frame, a rotatable drum mounted in the frame, means for clamping a master sheet to said drum, means for pressing copy sheets against the master sheet on said drum, means for guiding a master sheet to said clamping means, and means for aligning said securing means with said guide means, said aligning means comprising a lever pivoted on said frame, said lever being movable manually into a position wherein it engages said drum to prevent further rotation in the normal direction and stops it with its clamping means in alignment with said guide means, said lever being provided with means for opening said clamping means during the final movement of the drum to the position wherein it is stopped with its clamping means in alignment with said guiding means.

7. In a duplicating machine of the kind described, a frame, a rotatable drum mounted in said frame, means for securing a master sheet to said drum, means for pressing copy sheets against the master sheet on said drum, means for guiding a master sheet to said securing means, and means for aligning said securing means with said guide means, said aligning means comprising a member movably mounted on said frame, said member being movable into a position wherein it engages said drum to prevent further rotation thereof in the normal direction and stops it with its securing means in alignment with the guide means, said member having means for engaging and opening said securing means during the final movement of said drum into the position wherein it is stopped with its securing means aligned with said guide means.

ALFRED MARCHEV.
